DOOR ACTUATING MECHANISM

Herman C. Waldman, St. Louis, Mo.

Application August 22, 1933, Serial No. 686,199

12 Claims. (Cl. 187—54)

This invention relates generally to door-operators and, more particularly, to a certain new and useful improvement in electro-responsive door-actuating mechanisms adapted especially, though not exclusively, for automatically controlling the individual operation of doors for protecting the landings of an elevator.

My invention has for its prime object the provision of electro-responsive mechanism for controlling the operation of elevator-doors, more especially of the so-called "counterbalanced" type, wherein the door is divided substantially at its center, one door-section moving vertically upwardly, and the other door-section moving downwardly when the door is shifted to open position.

My invention has for another object the provision, in mechanisms of the character described, of a simple, sturdy, easily installed, and reliable door-operator occupying relatively small space and readily accommodated within the narrow confines of an elevator well without interfering with the elevator proper or the appurtenances thereof.

My invention has for still another object the provision, in a door-operator of the kind set forth, of means for electrically and mechanically interlocking the operation of the door with the movement of the elevator, so that the door may not be opened unless the elevator is at the landing protected by the door, and the elevator may not be moved from the landing when the door is opened.

My invention has for a further object the provision, in such door-operator, of means for automatically controlling or "timing" the movement of the door, so as to retard the speed of the door or door-sections as the same approach the termini of their travel for avoiding shocks to, and slamming of, the door, and for insuring that, if for any reason the door is shifted from fully closed or opened position, the same will be automatically restored to its fully closed or open position.

And with the above and other objects in view, my invention resides in the novel features of form, construction, arrangement and combination of parts hereinafter described and pointed out in the claims.

In the accompanying drawings (three sheets),—

Figure 1 is a rear elevational view of an elevator landing-door equipped with actuating mechanism of my invention;

Figure 2 is a side elevational view of the door

and its actuating mechanism, the wall of the elevator-well being shown in section;

Figure 3 is a top-plan view of the door and its actuating mechanism, the wall of the elevator-well being shown in section and the elevator proper being fragmentally shown;

Figure 4 is an enlarged vertical sectional view of the zone-switch of the mechanism;

Figure 5 is an enlarged front or chain-side view of the drive-head of the mechanism;

Figure 6 is an enlarged rear or elevator-well side view of the drive-head of the mechanism;

Figure 7 is an enlarged top-plan view, partly broken away and in section, of the mechanism;

Figure 8 is a horizontal sectional view of the cam switch of the mechanism;

Figure 9 is a transverse sectional view of the cam switch;

Figure 10 is a detail sectional view of one of the timer cams and its switch lever; and

Figure 11 is a wiring diagram of an installation of the mechanism.

Referring now more in detail and by reference characters to the drawings, which illustrate a practical embodiment of my invention, A designates a conventional form of electrically operated elevator, which, by mechanism not shown, is actuatable for vertical travel in an elevator-well or shaft B preferably, though not necessarily, constructed of brick masonry or other similar fire-proof material, merely the front wall 1 of which is shown.

2 designates one of the landings, as a floor or the like, to be serviced by the elevator A, the wall 1 of the elevator-well B having an aperture 35 or opening 3 disposed at the landing 2 for access therefrom to the elevator A.

C designates a door-structure which, as in the present instance, preferably, though not necessarily, comprises a pair of superposed upper and lower vertically movable sections 4, 5, respectively, disposed for travel in suitably spaced vertical guides 7, 7', attached to the face 6 of the wall 1 adjacent the respective jambs of the opening 3, as best seen in Figure 3.

Normally, the door-sections 4, 5, are disposed in opposing meeting relation for spanning across, and effecting closure of, the opening 3, the upper section 4, however, being shiftable upwardly until it is wholly above the lintel of the opening 3, and the lower section 5 being shiftable until it is wholly below the sill of the opening 3, for disposing the door C in opened position.

The door-sections 4, 5, are actuatable by a door-operator mechanism D, which includes a pair of

chains 8 looped over respective sheaves 9, 9', and attached at one end to brackets 10 which project laterally from the respective opposite sides of the lower margin of the upper door-section 4, while, 5 at their other end, the respective chain-loops 8 are engaged with the upper end of respective chain-rods 11 extending upwardly from corresponding ears or brackets 12 projecting laterally from the upper margin of the lower section 5, 10 the weight of the one door-section thus counterbalancing the weight of the other. At its lower end, each rod 11 has threaded thereon a pair of jam-nuts 13 for impinging the respective upper and lower faces of the ears 12, whereby the rod 15 11 may be adjustably disposed for regulating the position of the sections 4, 5, with respect to the opening 3.

The sheave 9, which supports one of the chains 8, is mounted on a shaft 14 journaled for rotation in a housing 15 attached, as by suitable ears 16, to the adjacent door-guide 7, the sheave 9 projecting peripherally through a suitable slot provided in the guide 7. In a similar manner, the sheave 9', which supports the other chain 8 on the opposite side of the door-structure C, is mounted on a shaft 17 journaled for rotation in a housing 18 attached, as by suitable ears 19', to the adjacent door-guide 7', the sheave 9' likewise projecting peripherally through a suitable 25 slot provided in the guide 7'. The housings 15, 18, it may here be pointed out, are interchangeably mountable on the guides 7, 7', as may best 30 serve the intended purpose.

Formed in the shaft-wall 1 in registration with 35 and between the housings 15, 18, is a channel 19, into which the shafts 14 and 17 endwise project, as does also a stub-shaft 21 on the housing 15. Most conveniently, it may be said, the channel or chase 19 may be constructed by merely setting back two or three courses of the brickwork 40 transversely, and in the face 6, of the shaft-wall 1.

At its said projecting end, the shaft 14 supports a driving sprocket 20, and supported for rotation on the projecting end of the shaft 21 below the plane of, and in registration with, the sprocket 20, is an idler-sprocket 22. Between the housing 15 and the sprocket 20, the shaft 21 pivotally supports an upstanding lever 23, which, intermediate its ends, rotatably supports an upper 45 idler-sprocket 24 disposed above the plane of, and likewise in registration with, the sprocket 20.

An endless chain 25 is trained or reeved over the lower idler-sprocket 22, the driving sprocket 20, and the upper idler-sprocket 24, in the order 50 named, and from the latter extends longitudinally in the chase 19 to and over a driven sprocket 26 mounted on the shaft 17, the chain 25 then returning in the chase 19 to the lower idler-sprocket 22, the arrangement being such that the shaft 17 is actuated reversely of and by the 55 shaft 14.

At its upper or free end, the lever 23 is provided with a lug 27, through which is threaded an adjusting screw 28, which at its one end impinges a stop 29 projecting upwardly from the housing 15, whereby, by manipulating the screw 28, the sprocket 24 on the lever 23 may be shifted 60 suitably for tensioning the chain 25 as circumstances may require.

Within the housing or shell 15, the shaft 14 carries a gear 30 preferably of the helical type, which meshes with a helical pinion 31 formed on a shaft 32, the latter preferably comprising 65 an extension of the rotor-shaft of a prime-mover 70 in the form of a motor 33 mounted on the shell 75

15. Preferably the frame of the motor 33 includes a bell-end portion 34 having upper and lower ears 35 and a laterally extending bracket or leg 36, whereby the motor 33 may with ease and facility be attached to and supported by the 5 housing 15.

Preferably, also, the motor shaft 32 is supported at its outer end in a suitably adjustable bearing 37 for effecting proper meshing engagement of the pinion 31 with the gear 30. 10

Mounted in suitable position on one of the door-guides 7, is a so-called "zone-switch" E, which includes a housing or shell 38 pivotally supporting at its upper end, as at 39, a bell-crank or lever 40, whose shorter or horizontal arm has 15 a link-connection, as at 41, with a plunger 42 vertically reciprocable in suitably spaced guides 43 projecting from the rear wall of the housing 38.

Mounted on and spanning between the guides 20 43, is an insulation-block 44, in and through which are mounted three vertically spaced electrical conducting contacts 45. On the plunger 42, are correspondingly spaced brackets 46 carrying suitable insulation-blocks 47 supporting, in 25 turn, suitable electrical conducting contactors 48 for cooperative engagement with the respective contacts 45. For purposes of description, the two upper pairs of cooperating contacts 45 and contactors 48 will be designated as the door-operator switches 49, 50, respectively, and the lower pair of contact 45 and contactor 48 will be designated as the elevator-operator switch 51.

A spring or like tensional member 52 is mounted 35 suitably on the plunger 42 for normally biasing the same toward the upper extremity of its movement, the door-operator switches 49 and 50, at such time, being in circuit-opening position, and the elevator-operator switch 51 being then in circuit-closing position for purposes presently appearing. 40

On its longer or upstanding arm, the lever 40 adjustably carries a ratchet-plate 53 having a series of serrations or teeth 54 for meshing engagement with a corresponding series of teeth on 45 a ratchet-arm 55 suitably fixed upon and upstanding from the adjacent ear 12 of the lower-door 5.

The teeth 54 are so arranged that, while the door-section 5 may be shifted upwardly in door-closing direction for ratchet movement of the arm 55 over the plate 53 against the bias of the spring 44, the teeth 54 on the plate 53 so normally engage the arm 55 as to prevent reverse or downward movement of the arm 55 for anchoring 55 the lower door-section 5, through the lever pivot 39 and the housing 38, to the door-guide 7, whereby the door-structure C, when in closed position, is securely latched against reverse or opening movement thereof. 60

At its upper end, the longer vertical arm of the lever 40 carries a roller 56 constructed of rubber or other suitable material, which normally projects into the elevator-well B in registration with the path of travel of a so-called "retiring-cam" 65 57 mounted on the elevator A. The cam 57 is of a type well known in the art, and it suffices here merely to say that, when the controller on the elevator A (not shown) is moved to its first notch, preliminary to initiating movement of the elevator A, a suitable prime-mover in the form of a motor 58, mounted on the elevator A, actuates the cam 57 for withdrawing or retiring the cam to inoperative position, but when the controller on the elevator is in neutral position for cessa- 70 75

tion of movement of the elevator A, the motor 58 is de-energized and the cam 57 is automatically projected so as to engage the roller 56 as the elevator A in its movement comes opposite the landing 2.

On engagement of the cam 57 with the roller 56, the lever 40 is rocked on its pivot 39 and the plunger 42 is thereby shifted downwardly in the housing 38, whereupon the contactor 51 is disengaged from the contact-pins 47, while the contactors 49 and 50 engage the pins 45, 46, respectively. At the same time, on such movement of the lever 40, the ratchet-plate 53 is disengaged from the arm 55, and the door-structure C there-by unlatched for permitting opening movement thereof, as will presently more particularly appear.

A latch-dog 128 is pivotally mounted on the housing 38 and is provided on its under-face with a series of notches or steps 129 co-operable with a lug 130 projecting from the lever 40 and so disposed that, when the lever 40 is rocked for unlatching the door-structure C, the lug 130 is moved to registration with one of the notches 129.

The dog 128, however, projects also into the path of movement of a lug 131 projecting from the ratchet-arm 55 of the door-section 5, whereby, when the door-section 5 is in closed position, the lug 131 engages the dog 128 for holding the same out of engagement with the lug 130. But if the door C be now opened, the section 5 moves downwardly for disengaging the lug 131 from the dog 128, whereby the dog 128 is free to drop upon the lug 130 for causing the latter to enter a notch 129, thereby latching the lever 40 securely in its rocked position until the door-section 5 is again raised for causing the lug 131 to lift the dog 128 for disengaging the same from the lug 130.

Mounted in suitable position, preferably at the upper end of the elevator-well B, is a rotary door position responsive controller or switch F, which includes a housing 59, journalled in which is a cam-shaft 60, and mounted on one end of the shaft 60, is a gear 61 which meshes with a pinion 62 on a stub-shaft 63, the latter, in turn, carrying a sprocket-wheel 64 disposed over the elevator-well B.

Trained over the sprocket 64, is a chain 65 having one of its ends attached to a counter-weight 66 shiftably guided in a vertical tube 67, as best seen in plan in Figure 8. To the other end of the chain 65, is attached a wire or tape 68, which descends to the bottom of the elevator well B, where a suitably attached weight 69 serves merely for maintaining the chain 65 in taut condition.

At each door-structure C, the tape 68 passes through a suitably apertured lug 70 attached to an adjacent ear 12 of the particular lower door-section 5, the tape 68 being equipped with a series of collars 71 respectively adjustable on the tape 68 for normally, under bias of the counter-weight 66, engaging the underside of a corresponding lug 70, whereby, on opening-actuation of the door C, the lowering movement of the door-section 5 shifts the tape 68 downwardly for effecting rotation of the cam-shaft 60 in one or door-opening direction approximately one-half revolution, more or less, as may best serve the purpose.

The shaft 60 is preferably threaded substantially its entire length and carries a series of composite or two-part cams 72, 73, 74, 75, 76, 77, respectively, each composed of a pair of substantially similar cam-discs a, b, each having a dwell-portion for substantially one-half of its periphery

and a drop-portion for the remainder thereof. The cam-discs a, b, are adjustably mounted on the shaft 60, whereby the angular relationship of one cam-disc, as a, of a pair may be varied with respect to the other cam-disc b, so as to provide a resulting drop-portion c of the composite cam of suitable angular distance, as will presently appear. When properly so adjusted, the respective cam-discs a, b, are clamped firmly together by means of corresponding pairs of opposing nuts 78 threaded on the shaft 60, which nuts 78 may also be employed for properly spacing the cams 72, 73, 74, 75, 76, and 77, longitudinally on the cam-shaft 60.

Mounted suitably adjacent the rear wall of the housing 59, is a pivot shaft 79, which supports, at properly spaced intervals, a series of switch-levers 80, each carrying a roller 81 for respective co-operable engagement with the periphery of the cams 72, 73, 74, 75, 76, 77, also respectively.

On each switch-lever 80, is insulatably mounted at an end a resilient-member 82 of conducting material, whose other end is secured to an insulation-block 83 mounted on the rear wall of the housing 59 for biasing the roller 81 on the particular cam 72, 73, 74, 75, 76, 77, as the case may be, each resilient-member 82 being associated with, and conductively connected to, a terminal-post 84 also mounted on the insulation-block 83.

Each switch-lever 80 also carries a contactor 85 of current conducting material and conductively connected with the resilient-member 82, the contactor 85 being co-operable with a contact 86 mounted on an insulation-block 87 supported suitably across the front of the housing 59, the contact 86, in turn, being conductively connected to a corresponding terminal 88 also mounted on the block 87.

For purposes of description, the switching units composed of the several pairs of co-operable contactors 85 and contacts 86 will be referred to respectively as the cam switch 89, 90, 91, 92, 93, 94, respectively, operable for closure thereof by, and when a particular roller 81 drops into the portion c of, the cams 72, 73, 74, 75, 76, and 77, also respectively.

The function of the controller-switch F is to automatically control the actuation of the door-operator D, which is effected by means of a conventional form of magnetic reversing switch G 50 preferably mounted also in the housing 59. In the present instance, it may here be said, the motor 33 of the door-operator D is of the alternating current three-phase type, although, of course, other types of prime-mover may be employed, as may best serve the purpose.

For controlling such three-phase current, the reversing switch G is equipped with a first group of three normally open switches 95 operable for closure thereof by, and on energization of, a solenoid 96, the switches 95 being respectively connected on their one side to the three-phase main leads 97, 98, 99, of the source of power supply. The reversing switch G also includes a second group of three normally open switches 100 operable for closure thereof by, and on energization of, a solenoid 101, the switches 100 being likewise respectively connected on their one side to the three-phase leads 97, 98, 99. On de-energization of the solenoids 96, 101, the respective switches 95, 100, are automatically returned to normal open position as by suitably mounted tension members or springs 95', 100', respectively, as indicated in Figure 11.

On their other side, the respective groups of

switches 95, 100, are connected with trunk-leads 102, 103, 104, suitably enclosed in a conduit 105, which descends to the bottom of the elevator-well B. Opposite each zone-switch E, the trunk-leads 102, 103, are connected to the door-operator switches 49, 50, respectively, and from thence by motor-leads 106, 107, also respectively to the motor 33, the trunk-lead 104 being connected directly with the motor 33 by a lead 108.

10 The trunk-leads 102, 103, 104, are connected to the reversing switch G in such manner that, assuming the switches 49, 50, are first closed, closure of the switches 95 will actuate the motor 33 in one direction for opening the door C, and, when the switches 100 are closed, the motor 33 will be actuated in the other direction for closing the door C, the reversing switch G being suitably equipped with interlocking means, as diagrammatically illustrated at 109, for automatically opening one 15 group of switches, as 95, when the other group thereof, as 100, is closed, or vice-versa, in the 20 manner well known in the art.

The respective elevator-operator switches 51 of the several zone-switches E are connected in series by means of a lead 110 also preferably enclosed in the conduit 105. The lead 110 forms part of a loop-circuit included in the elevator-controlling circuit of the elevator-motor control-board (not shown), and it suffices here merely to say that, when, as is normally the case, all the switches 51 are closed, the elevator-controlling-circuit is effective for operations of the elevator A, whereas opening of any one of the switches 51 30 interrupts the controlling-circuit so that the elevator A may not be operated until that particular switch 51 is again closed.

One of the three-phase main leads, as 97, is extended to a snap or cut-out switch 111 mounted on the elevator A, which controls the supply of current, through a lead 112, to a pair of normally open push-button switches 113, 114, also mounted on the elevator A, the push-button switch 113 being, in turn, connected through a lead 115 with the switch 89 of the controller F, and the switch 114 being connected through a lead 116 with the switch 94 of the controller F.

The cut-out switch 111 is also connected through a second lead 117 with a pair of normally open push-button switches 118, 119, located 50 on the room side of the bottom-landing of the elevator-well B, the switch 118 being, in turn, connected with the lead 115 of the cam-switch 89, and the switch 119 being connected with the lead 116 of the cam switch 94. Finally, a third lead 55 120 connects the cut-out switch 111 with the cam switches, 90, 91, 92, 93, of the controller F.

It will be seen that the supply of current to the controller F is controlled, in the first instance, by the cut-out switch 111, and that the cam-switches 89 and 94 are further controlled by the push-button switches 113, 118, for the switch 89, and by the push-buttons 114, 119, for the cam-switch 94.

The cam-switches 89 and 92 are, in turn, connected by a lead 121 with one side of the solenoid 96, whose other side is connected to the main-lead 99. The cam-switches 91, 93, and 94 are connected by a lead 122 with the solenoid 101, whose other side is likewise connected to the main-lead 99. Thus, the solenoids 96, 101, are connected, through the several controlling cam switches as described, across one of the phases of the alternating current supply, in the present instance between the leads 97, 99, thereof.

75 The cam switch 90 is connected by a lead 123

with a so-called maintaining switch 124 forming a part of the reversing switch G and connected, in turn, with the lead 121 of the solenoid 96, the switch 124 being open when the main-switches 95 of the reversing switch G are open and the switch 124 being closed when the switches 95 are closed, for a purpose presently appearing.

In some installations, a switch 125 is provided on the elevator control-board, for example, in connection with the micro-leveling device, or other elevator-position responsive switch, not forming a part of this invention, and is automatically operable responsively to movement of the elevator for momentarily closing the switch 125 when the elevator A is opposite any one of the landings 2, as well known to those skilled in the art, and it will be observed that a suitable lead 126 is run from the lead 120 to the switch 125, and another lead 127 runs from the switch 125 to the cam-switch 89, whereby current may, if desired, be supplied directly through the switches 125 and 89 to the solenoid 96.

In use and operation, the conventional controller (not shown) on the elevator is brought to neutral position, which de-energizes the motor 58, and the cam 57 is automatically projected, in the well-known manner, common to such installations and not forming a part of this invention, and hence not deemed necessary of further description, into engagement with the roller 56 of the zone-switch E at that particular landing 2, to which the elevator A is brought, as shown by dot-dash lines in Figure 11.

On engagement of the cam 57 with the roller 56, the zone-switch E is actuated for closing the switches 49, 50, thus connecting the door-operator motor 33 with the trunk-leads 102, 103. At the same time, the switch 51 is opened, thus interrupting the elevator-operator circuit, so that the elevator A may not thereafter be moved during the door-opening operation, that is, until the door C is closed and the zone-switch E is reversely actuated, as presently appearing.

The cam 72 of the controller F is normally, that is, when the door C is closed, disposed for closing the switch 89 of the controller F. The elevator-attendant, accordingly, desiring to open the door C, actuates the push-button 113 for energizing the lead 116, current being hence, through the normally closed switch 89 and lead 121 supplied to the solenoid 96 for closing the switches 95 of the reversing switch G.

On closure of the switches 95, current is supplied from the mains 97, 98, 99, through the trunk-leads 102, 103, 104, to the particular zone-switch E which has been actuated by the cam 57, and from thence through the motor-leads 106, 107, 108, to the motor 33 of the corresponding door-operator D, thereby initiating door-opening actuation of the door-sections 4, 5, of the particular door C of the landing at which the elevator A is positioned, it being recalled that, when the switches 95 are closed, the switch 124 is also closed.

As the door C starts to open, the dog 128 is dropped for latching the switch E in its shifted position for interrupting the circuit of the elevator motors, as described, and the lower-door section 5 likewise actuates the tape 68, which latter, in turn, rotates the shaft 60 of the controller F. Rotation of the shaft 60 actuates the cam 73 for closing the switch 90, current being thus supplied from the lead 120 to the lead 123 through the now closed maintaining switch 124 to the solenoid 96 for maintaining the switches 95

in closed position irrespective of further manipulation of the push-button switch 113.

As the door-sections 4, 5, approach within approximately two or three inches of the termini of their respective door-opening movements, the cams 72 and 73 act for opening their respective switches 89 and 90, thereby de-energizing the solenoid 96, thereupon the switches 95 return automatically to open position for disconnecting the motor 33 from the main-leads 97, 98, 99. At the same time, the cam 74 momentarily closes the switch 91 for energizing the solenoid 101, which closes the switches 100 and re-connects the motor 33 with the main-leads 97, 98, 99.

15 The current-supply to the motor 33 is now reversed, that is to say, the motor 33 is "plugged" for opposing the opening-movement of the door-sections 4, 5, which reduces the momentum and checks the speed of the door-sections 4, 5, as they approach fully open or closed position.

16 The cam 74 then opens the switch 91, for de-energizing the solenoid 101, whereupon the switches 100 are opened by the spring 100' for de-energizing the motor 33 while the cam 75 momentarily closes the switch 92 for now energizing the solenoid 96, whereupon the switches 95 are again momentarily closed for motivating the door-motor 33 for quietly bringing the door C to fully open position without slamming or shock to the mechanism, whereupon switch 92 is again opened by the roller 81 riding up upon the raised portion of the cam 75 for de-energizing the solenoid 96, the spring 95' then opening the switches 95 for cutting off the motor 33 from its source of power. Should the door C for any reason tend to move from open position, the cam 75 will act for momentarily closing switch 92 for automatically restoring the door C to its fully open position.

20 40 In the meantime, the cam 76, immediately following initiation of opening movement of the door C, closes the switch 93, which connects the solenoid 101 with the lead 115. However, energization of the solenoid 101, through the switch 93, will not be effected until the "close" push-button 114 is manipulated by the elevator-attendant.

25 50 In its normal course, the door C proceeds to fully open position, the cam 76, during such period, acting for effecting continued closure of the switch 93. The elevator-attendant then, desiring to close the door, presses the push-button switch 114 to closed position, current then flowing through the switch 114, lead 116, switch 93, and lead 122 to the solenoid 101 for closing the switches 100, whereupon the motor 33 is actuated in reverse direction for drawing the door-sections 4, 5, together.

55 60 The solenoid 101 is not, however, equipped with a "maintaining" switch, the push-button switch 114 being designated as of the "constant-pressure" type, that is to say, the push-button switch 114 must be continuously manipulated to closed position by the elevator-attendant during closing movement of the door C, any relaxation in manipulation of the switch 114 resulting in interruption of the motor-circuit and stoppage of the closing movement of the door C. However, re-closure of the switch 114 will effect resumption 65 of closing movement of the door C.

70 75 The ensuing movement of the door-section 5 toward closed position releases the tape 68, whereupon the weight 68 acts for reversely revolving the shaft 60. Consequently, as the door-sections 4, 5, are brought together in closed position, the

cam 76 opens the switch 93 for interrupting the current-supply to the solenoid 101, the switches 100 thereupon being automatically opened by the spring 100' for disconnecting the motor 33 from the main leads 97, 98, 99.

5 The door-sections 4, 5, being deprived of the power of the motor 33, slow down in their closing-movement; however, as the door-sections 4, 5, approach closed position, the cam 77 acts for momentarily closing the switch 94 for supply of current to the solenoid 101 from the lead 120, whereupon the switches 100 are momentarily closed for again connecting the motor 33 with the leads 97, 98, 99, for motivating the door-sections 4, 5, to final closed position, at which time 15 the switch 94 is again opened by the roller 81 riding up upon the raised portion of the cam 77 for de-energizing the solenoid 101, the spring 100' then opening the switches 100 for cutting off the motor 33 from its source of power. The purpose of the switch 94 is to effect "self-closing" of the door C if for any reason the door-sections 4, 5, should become separated from their normally closed position. Thus, for example, should the door-sections 4, 5, rebound from closed-position, the cam 77 acts automatically for closing the switch 94, with ensuing motivation of the motor 33 for again closing the door.

20 30 On closure of the door C, the dog 128 is lifted for releasing the lever 40. For starting the elevator A, the attendant shifts the elevator controller for example to its first notch position, which, in the customary manner, energizes the motor 58 for "withdrawing" the cam 57. Thereupon, the roller 56 being released from the cam 35 57, and the lever 40 released from the dog 128, the plunger 42 is shifted upwardly by the spring 52 for opening the door-operator switches 49, 50, and closing the elevator-operator switch 51, the ratchet plate 53 being, at the same time, latched to the ratchet arm 55.

35 40 The elevator A may now be moved from the particular landing 2, but the door C may not be opened, since it is latched, by means of the ratchet plate 53 and arm 55, against manual manipulation and may not be electrically operated inasmuch as the zone switch E has acted for interrupting the circuit of the motor 33.

45 50 It may here be pointed out that the solenoids 96 and 101 are so constructed that, when one switch-group, as 95, is in circuit-closing position, the solenoid 96 thereof has a greater magnetic power, as may be said, than that of the solenoid 101, the switches 100 thereof being then in circuit-opening position. Consequently, when, during the opening movement of the door C, the switch 94 is momentarily closed for energizing the solenoid 101, the magnetic power of the previously energized solenoid 96, acting through the device 109, prevents the closure of the switches 100. 55 And, similarly, but in reverse order, when, during the closing movement of the door C, the switch 92 is momentarily closed for energizing the solenoid 96, the same is rendered ineffective by the power of the previously energized solenoid 101.

60 65 And it may be pointed out that, if both push-button switches 113, 114, are manipulated at the same time, and the switches 89 and 93 are likewise closed, the solenoids 96 and 101 will merely "buck" one another without effecting closure of either of the switches 95, 100.

70 75 The switches 118, 119, are "room-side" switches operable by a person not in the elevator A for purposes of meeting an emergency or the like.

The switches 118, 119, have the same form and function as the switches 113, 114, respectively, and further description thereof is deemed unnecessary.

5 It will be seen that, in all cases, manipulation of the push-buttons 113, 114, and 118, 119, will be ineffective for motivation of the door-operator D unless the retiring cam 57 has been projected for actuating the zone switch E for closing the circuit of the motor 33.

10 The car position responsive switch 125 has the same functions as the push-button switch 113. The switch 125 is, as well known in the art, actuated automatically to closed position as the elevator A comes opposite each landing 2, which in this case energizes the solenoid 96 through the leads 126, 127, switch 89, and lead 121. The solenoid 96 then closes the switches 95, as the elevator A passes each landing, but without effect on the door-operator D unless, as has been said, the zone switch E has been operated by the cam 57 for closing the circuit of the motor 33.

15 In an emergency, the snap-switch 111 may be opened, which interrupts the supply of current to the leads 112, 115, 116, 120, for immediately stopping movement of the door-operator D.

20 It will be seen that each door of the series thereof served by the elevator has its individual motor or unit-drive complete in itself, irrespective of any other door of the series, each door, further, being selectively controlled and operated through the means of its zone switch E and the retiring cam 57 and push-buttons 113, 114, on 25 the elevator, and it may be pointed out that the controller F may be located conveniently in any suitable place in the elevator-well B, though preferably, as has been said, the controller F is located in the elevator-pent-house.

30 40 The use of a reduction gearing in the housing 15 permits the employment of a high-speed motor 23 of relatively small dimensions, and, by the described method of disposing the chain 25 in the wall chase 19, the installation of the operator D will occupy but little space in the elevator-well, 35 in no manner interfering with the location and movement of the elevator A in its well B.

45 The controller F controls the speed of the door C as it comes to fully opened or closed position and acts to prevent "banging" or slamming of the door sections 4, 5. The controller F is effective, however, only through the zone-switch E for controlling the actuation of the particular door at the landing where the elevator A may be at 50 rest and can be controlled by a switch on the elevator-car, on the "room-side" of the well B, as described, or, further, by means of switch 125, through the "micro-leveling" or similar device of the elevator-drive, as may best serve the purpose.

55 60 The wires composing the several circuits controlling the operators D may conveniently be contained in a single conduit 105 extending the height of the well B, thus providing a highly compact electrical installation.

65 It will be seen that the invention accomplishes its purposes, and it will be understood that changes and modifications in the several parts of the mechanism may be made and substituted for those herein shown and described without departing from the nature and principle of my invention.

70 Having thus described my invention, what I claim and desire to secure by Letters Patent is,—

75 1. A well having a landing, an elevator arranged for travel in the well, a door comprising a

pair of oppositely shiftable sections cooperably approachable for obstructing access to the landing from the well, means including an electric circuit for actuating the elevator, and means for controlling operation of the door sections, said latter means comprising a door-operating electric motor and its circuit, a plurality of stationary door-contacts included in the door-motor circuit and a stationary elevator contact disposed in spaced tandem relation to the door-contacts and included in the elevator circuit, a shiftable bar common to the stationary contacts, cooperable contacts carried by the bar for engagement respectively with the stationary door and elevator contacts, the elevator contacts being normally in circuit-closing engagement and the door contacts being normally open, a bell-crank lever pivotally connected to said bar, a cam on the elevator for actuating the bell-crank for shifting the bar for engaging the door contacts and disengaging the elevator contacts, a first manual switch on the elevator operable for initiating movement of the door-sections from closed to open position, a first automatic switch operable by and on movement of the door sections from closed toward open position for controlling actuation of the door motor for bringing the door sections to open position, a second manually operable switch on the elevator for initiating movement of the door sections from open to closed position, a second automatic switch operable by and on movement of the door sections from open toward closed position for controlling actuation of the door motor for bringing the door sections to closed position, a pivotally mounted latch-dog 30 cooperable with said lever for releasably retaining the same in actuated position, and a lug on a door section for releasing the dog from engagement with the lever when the door sections are in closed position.

ward closed position for controlling actuation of the door motor for bringing the door sections to closed position, a lug projecting from the lever, a latch-dog pivotally mounted on the housing and provided on its under face with a series of notches cooperable with said lug for releasably retaining said lever in actuated position, and a lug on a door section for lifting the dog out of engagement with the lug when the door sections are in closed position.

3. A well having a landing, an elevator arranged for travel in the well, a door comprising a pair of oppositely shiftable sections cooperably approachable for obstructing access to the landing from the well, means including an electric circuit for actuating the elevator, and means for controlling operation of the door sections, said latter means comprising a door-operating electric motor and its circuit, a plurality of stationary door-contacts included in the door-motor circuit and a stationary elevator contact disposed in spaced tandem relation to the door-contacts and included in the elevator circuit, a shiftable bar common to the stationary contacts, cooperable contacts carried by the bar for engagement respectively with the stationary door and elevator contacts, the elevator contacts being normally in circuit-closing engagement and the door contacts being normally open, a bell-crank lever pivotally connected to said bar, a cam on the elevator for actuating the bell-crank for shifting the bar for engaging the door contacts and disengaging the elevator contacts, a pivotally mounted latch-dog cooperable with said lever for releasably retaining the same in actuated position, and a lug on a door section for releasing the dog from engagement with the lever when the door sections are in closed position.

4. A well having a landing, an elevator arranged for travel in the well, and a door comprising a pair of oppositely shiftable sections cooperably approachable for obstructing access to the landing from the well, in combination with means including a first motor and its circuit for actuating the elevator, and means for controlling operation of the door sections, said latter means comprising a second electric motor and its circuit, a fixed door contact and a fixed elevator contact disposed in spaced tandem relation and included in the respective circuits, a shiftable bar common to said contacts, cooperable contacts carried by the bar for engagement respectively with said fixed door and elevator contacts, the elevator contacts being normally in engagement for closing the first circuit and the door contacts being normally spaced for opening the second circuit, a shiftable bell-crank lever pivotally connected to the bar, a cam on the elevator for actuating the bell-crank for shifting the bar for engaging the door contacts for closing the second circuit and spacing the elevator contacts for opening the first circuit, a rotary switch mechanism included in the second circuit, a member depending in the well having operative connection with said switch mechanism and engageable by one of the door sections responsively to door section movement for actuating the switch mechanism for controlling the direction and amount of door movement, a pivotally mounted latch-dog cooperable with said lever for releasably retaining the same in actuated position, and a lug on a door section for releasing the dog from engagement with the

lever when the door sections are in closed position.

5. A well having a landing, an elevator arranged for travel in the well, and a door comprising a pair of oppositely shiftable sections cooperably approachable for obstructing access to the landing from the well, in combination with means including a first motor and its circuit for actuating the elevator, and means for controlling operation of the door sections, said latter means comprising a second electric motor and its circuit, a fixed door contact and a fixed elevator contact disposed in spaced tandem relation and included in the respective circuits, a shiftable bar common to said contacts, cooperable contacts carried by the bar for engagement respectively with said fixed door and elevator contacts, the elevator contacts being normally in engagement for closing the first circuit and the door contacts being normally spaced for opening the second circuit, a shiftable bell-crank lever pivotally connected to the bar, a cam on the elevator for actuating the bell-crank for shifting the bar for engaging the door contacts for closing the second circuit and spacing the elevator contacts for opening the first circuit, a rotary switch mechanism and a third circuit for controlling the second circuit, a member depending in the well having operative connection with said switch mechanism and engageable by one of the door sections responsively to door section movement for actuating the switch mechanism for controlling the direction and amount of door movement, a first manually operable switch on the elevator also included in the third circuit operable for closing the door circuit for initiating movement of the door sections from closed to open position, and a second manually operable switch on the elevator also included in the third circuit for regulating movement of the door sections from open to closed position, movement of the door sections from open to closed position continuing only so long as the second switch is in circuit-closing position.

6. A well having a landing, an elevator arranged for travel in the well, and a door comprising a pair of oppositely shiftable sections cooperably approachable for obstructing access to the landing from the well, in combination with means including a first motor and its circuit for actuating the elevator, and means for controlling operation of the door sections, said latter means comprising a sheave at each side of the door, flexible members each engaging a sheave for connecting the door sections at their respective opposite sides, a driving sprocket associated with one of the sheaves, a driven sprocket associated with the other sheave, a pair of upper and lower idler sprockets disposed on opposite sides of the driving sprocket, a motor and its controlling circuit for actuating the driving sprocket, a sprocket chain trained over the idlers and having a loop intermediate the idlers substantially embracing the driving sprocket, said chain being extended across the well from the respective idler sprockets for substantially embracing the driven sprocket, a switch mechanism for controlling the motor circuit, a member depending in the well having operative connection with the switch mechanism, and a projection on one of the door sections for engaging said member responsively to door section movement for actuating the switch mechanism for controlling the motor circuit.

7. A well having a landing, an elevator arranged for travel in the well, and a door compris-

ing a pair of oppositely shiftable sections cooperably approachable for obstructing access to the landing from the well, in combination with means including a first motor and its circuit for actuating the elevator, and means for controlling operation of the door sections, said latter means comprising a sheave at each side of the door, flexible members each engaging a sheave for connecting the door sections at their respective opposite sides, 5 a driving sprocket associated with one of the sheaves, a driven sprocket associated with the other sheave, a pair of upper and lower idler sprockets disposed on opposite sides of the driving sprocket, a motor and its controlling circuit 10 for actuating the driving sprocket, a sprocket chain trained over the idlers and having a loop intermediate the idlers substantially embracing the driving sprocket, said chain being extended across the well from the respective idler sprockets 15 for substantially embracing the driven sprocket, a switch mechanism for controlling the motor circuit, a member depending in the well having operative connection with the switch mechanism, a projection on one of the door sections for engaging said member responsively to door section movement for actuating the switch mechanism for controlling the direction and amount of door movement, a first manually operable switch on the elevator also included in the switch mechanism circuit operable for closing the door circuit for initiating movement of the door sections from closed to open position, a second 20 manually operable switch on the elevator also included in the switch-mechanism circuit for regulating movement of the door sections from open to closed position, and co-operable devices for adjustably tensioning the chain for preserving the horizontal alignment of the door sections for insuring the accuracy of actuation of the switch mechanism.

8. A well having a landing, an elevator arranged for travel in the well, and a door comprising a pair of oppositely shiftable sections cooperably approachable for obstructing access to the landing from the well, in combination with means including a first motor and its circuit for actuating the elevator, and means for controlling operation of the door sections, said latter means comprising a sheave at each side of the door, flexible members each engaging a sheave for connecting the door sections at their respective opposite sides, a driving sprocket associated with one of the sheaves, a driven sprocket associated with the other sheave, a pair of upper and lower idler sprockets disposed on opposite sides of the driving sprocket, a motor and its controlling circuit for actuating the driving sprocket, a sprocket chain trained over the idlers and having a loop intermediate the idlers substantially embracing the driving sprocket, said chain being extended across the well from the respective idler sprockets for substantially embracing the driven sprocket, a switch mechanism for controlling the motor circuit, a member depending in the well having operative connection with the switch mechanism, a projection on one of the door sections for engaging said member responsively to door section movement for actuating the switch mechanism for controlling the direction and amount of door movement, a first manually operable switch on the elevator also included in the switch mechanism circuit operable for closing the door circuit for initiating movement of the door sections from closed to open position, a second manually operable switch on the elevator also included in the switch-mechanism circuit for regulating movement of the door sections from open to closed position, and co-operable devices for adjustably tensioning the chain for preserving the horizontal alignment of the door sections for insuring the accuracy of actuation of the switch mechanism.

9. A well having a landing, an elevator arranged for travel in the well, and a door comprising a pair of oppositely shiftable sections cooperably approachable for obstructing access to the landing from the well, in combination with means including a first motor and its circuit for actuating the elevator, and means for controlling operation of the door sections, said latter means comprising a sheave at each side of the door,

flexible members each engaging a sheave for connecting the door sections at their respective opposite sides, a driving sprocket associated with one of the sheaves, a driven sprocket associated with the other sheave, a pair of upper and lower idler sprockets disposed on opposite sides of the driving sprocket, a motor and its controlling circuit for actuating the driving sprocket, a sprocket chain trained over the idlers and having a loop intermediate the idlers substantially embracing the driving sprocket, said chain being extended across the well from the respective idler sprockets for substantially embracing the driven sprocket, a switch mechanism and its circuit for controlling the motor circuit, a member depending in the well having operative connection with the switch mechanism, means on one of the door sections for engaging said member responsively to door section movement for actuating the switch mechanism for controlling the direction and amount of door movement, a first manually operable switch on the elevator also included in the switch mechanism circuit operable for closing the door circuit for initiating movement of the door sections from closed to open position, a second manually operable switch on the elevator also included in the switch-mechanism circuit for regulating movement of the door sections from open to closed position, and co-operable devices for adjustably tensioning the chain for preserving the horizontal alignment of the door sections for insuring the accuracy of actuation of the switch mechanism.

10. A well having a landing, an elevator arranged for travel in the well, and a door comprising a pair of oppositely shiftable sections cooperably approachable for obstructing access to the landing from the well, in combination with means including a first motor and a circuit for actuating the elevator, and means for controlling operation of the door sections, said latter means comprising a sheave at each side of the door, flexible members each engaging a sheave for connecting the door sections at their respective opposite sides, a driving sprocket associated with one of the sheaves, a driven sprocket associated with the other sheave, a pair of upper and lower idler sprockets disposed on opposite sides of the driving sprocket, a door motor and its controlling circuit for actuating the driving sprocket, and a sprocket chain trained over the idlers and having a loop intermediate the idlers substantially embracing the driving sprocket, said chain being extended across the well from the respective idler sprockets for substantially embracing the driven sprocket.

11. A well having a landing, an elevator arranged for travel in the well, and a door comprising a pair of oppositely shiftable sections cooperably approachable for obstructing access to the landing from the well, in combination with means including a first motor and a circuit for actuating the elevator, and means for controlling operation of the door sections, said latter means comprising a sheave at each side of the door, flexible members each engaging a sheave for connecting the door sections at their respective opposite sides, a driving sprocket associated with one of the sheaves, a driven sprocket associated with the other sheave, a pair of upper and lower idler sprockets disposed on opposite sides of the driving sprocket, a door motor and its controlling circuit for actuating the driving sprocket, a sprocket chain trained over the idlers and having a loop intermediate the idlers substantially

embracing the driving sprocket, said chain being extended across the well from the respective idler sprockets for substantially embracing the driven sprocket, and cooperable devices for adjustably tensioning the chain for preserving the horizontal alignment of the door sections.

12. A well having a landing, an elevator arranged for travel in the well, and a door comprising a pair of oppositely shiftable sections cooperably approachable for obstructing access to the landing from the well, in combination with means including a first motor and its circuit for actuating the elevator, and means for controlling operation of the door sections, said latter means comprising a sheave at each side of the door, flexible members each engaging a sheave for connecting the door sections at their respective opposite sides, a driving sprocket associated with one of the sheaves, a driven sprocket associated with the other sheave, a pair of upper and lower idler sprockets disposed on opposite sides of the driving sprocket, a motor and its controlling circuit for actuating the driving sprocket, a sprocket chain trained over the idlers and having a loop intermediate the idlers substantially embracing the driving sprocket, said chain being extended across the well from the respective idler sprockets for substantially embracing the driven sprocket, a rotary switch mechanism and its circuit for

controlling the door-motor circuit for controlling the direction and amount of door movement, a member depending in the well having operative connection with the switch mechanism and engageable by a door section responsively to door section movement for actuating the switch mechanism, a fixed door contact included in the door-motor circuit, a fixed elevator contact disposed in tandem relation with the door contact and included in the elevator-motor circuit, a shiftable bar common to said contacts, cooperable contacts carried by the bar for engagement respectively with said fixed door and elevator contacts, the elevator contacts being normally in engagement for closing the elevator-motor circuit and the door contacts being normally spaced for opening the door-motor circuit, a shiftable bell-crank lever pivotally connected to the bar, a cam on the elevator for actuating the bell-crank for shifting the bar for engaging the door contacts for closing the door-motor circuit and spacing the elevator contacts for opening the elevator-motor circuit, and manually operable switches included in the switch-mechanism circuit and carried by the elevator for initiating movement of the door sections in one or the other direction.

HERMAN C. WALDMAN.
